UNITED STATES PATENT OFFICE

2,213,196

COMPRESSOR

Warren F. Bartholomew, Michigan City, Ind., assignor to Sullivan Machinery Company, a corporation of Massachusetts

Application April 16, 1938, Serial No. 202,378

9 Claims. (Cl. 180—53)

My invention relates to motor-driven compressors, and more particularly to motor-driven compressors of the portable self-propelled type.

The mounting of compressors upon motor-driven trucks and the driving of these compressors by the truck engines, provide a piece of equipment which meets a variety of needs. In providing such equipment, a problem has been found to exist due to the fact that the truck engine builders, particularly on five or ten-ton trucks, provide an automatic speed-regulating device on the engine carburetor which limits the road speed of the truck to a definite value by limiting the engine speed. This governed engine speed is frequently too high for the desired compressor speed, and the expedient of providing a second governor which may be cut in to regulate the speed of the engine when the latter is driving the compressor, is precluded in many instances by lack of available space and at times by the impossibility of effecting the necessary rearrangement of parts due to complications of mechanism.

A very common type of governing device for truck engines includes a butterfly valve governed by the vacuum in the engine intake and designed to be moved in a closing direction by increased intake vacuum and to be opened, as by a spring. I have found that by providing suitable means in association with the governor of the truck engine it is possible to increase the responsiveness of the governor to factors which vary with the engine speed, and to provide for the effecting of this increased responsiveness upon a transfer of the drive of the engine from the truck wheels to the compressor. For example, the responsiveness of a speed-responsive governor can be changed by providing for a diminished resistance to the motion of the centrifugally actuated weight or weights upon the establishment of driving connections for the compressor, and in a preferred embodiment of the invention, in which the same is incorporated in a system utilizing a vacuum-controlled throttle of the type above mentioned, means may be provided to increase the responsiveness to vacuum changes by providing for the subtraction of resistance to butterfly valve closure upon establishing compressor driving connections, and to increase such resistance upon transfer of the drive to the truck wheels. Desirably, connections may be made so that the shifting of the drive will be automatically attended by the change in responsiveness of the governor. It will be apparent that a common engine drive for a compressor and any other apparatus may give rise to

a similar problem, and my invention, in its broader aspects, includes all such installations in which its feature of altered governing with change in driven instrumentality occurs.

It is an object of my invention to provide an improved control for an engine which drives alternately a compressor and another device calling for a different speed of engine operation. It is another object of my invention to provide an improved control for an engine and a plurality of devices alternatively driven thereby, for altering the regulation of the engine upon change in the drive from one to another of said devices. It is a further object of the invention to provide an improved portable compressor having a driving engine which also provides the power for transport purposes and which has controlling means establishing a normal full speed for the latter purposes in excess of desirable compressor speeds, and to provide for concurrent adjustments of the controlling means with transfers of the drive from compressor to truck wheels and vice versa. Still another object of the invention is to provide an improved control for an intake-vacuum controlled throttle. Yet a further object is to provide an improved controlling means for an engine transmission and for the governor of the engine driving the transmission. Other objects and advantages of the invention will hereinafter appear.

In the accompanying drawings, in which, for purposes of illustration, one form which the invention may assume in practice has been shown:

Fig. 1 is a longitudinal sectional view through a truck, showing the engine, the compressor and a portion of the transmission and power take-off.

Fig. 2 is an enlarged central horizontal section through the power take-off, approximately on the plane of the section line 2—2 of Fig. 1.

Fig. 3 is a fragmentary view on an enlarged scale, showing a portion of the control for the power take-off and the engine governor.

Fig. 4 is a side view, with parts removed, of a portion of the governor in the position occupied during compressor drive.

Fig. 5 is a corresponding end view of a portion of the governor mechanism.

Fig. 6 is a view corresponding to Fig. 4, showing the governor in position for road operation.

Fig. 7 is a view corresponding to Fig. 5, showing an end of the governor mechanism adjusted for road operation.

Fig. 8 is a vertical sectional view through the governor, showing details of construction.

55

Fig. 9 is a top view of the governor disconnected from the engine intake.

Fig. 10 is a view seen from the end of the governor, which corresponds to the lower end of Fig. 9 of the governor mechanism.

Fig. 11 is a vertical section on the line 11—11 of Fig. 9, showing the governor parts in full road speed position.

Fig. 12 is a similar view showing a position of the governor for full compressor drive speed.

Fig. 13 is a fragmentary section on the plane of the line 13—13 of Fig. 12.

Referring to the drawings, Fig. 1 will be observed to show a portion of the truck body, generally designated 1, a truck-driving engine 2, and a compressor 3 carried by the truck body. The split drive shaft, composed of sections 4, 5, 6, is driven through any suitable mechanism by the engine 2. It will be noted that the shaft section 4 is connected with the shaft section 6 by a universal joint 7, and that the shaft sections 5 and 6 may be connected together by mechanism within the split-shaft power-take-off device, which is generally designated 8. The shaft section 6, which is suitably journaled within a bearing 9, is maintained coaxial with the shaft section 5 by a bearing 11 mounted within the enlarged end 12 on the shaft portion 5, and carries a sleeve 13 which has fixed thereto a power drive-off pulley 14 of the multi-V-belt type. The sleeve 13 is journaled at 15 within the casing 16 of the power take-off mechanism and has clutch teeth 17 formed on its rearward end, adapted for engagement by clutch teeth 18 on a sliding clutch member 19 splined, as at 20, to the rearward end of the shaft section 6. The member 19 carries other teeth 21 adapted to mesh with clutch teeth 22 on the headed portion 12 on the shaft section 5. The shaft section 5 is journaled in bearings 24 supported within the casing 16 in the rearward end of the power take-off. A shipper device 25 is movable by a rod 26 and has a portion 27 engaging in an annular groove 28 in the clutch element 19. Operating means for the rod 26 includes a cross connection 29 and a longitudinally extending operating rod 30 connected to the lower end 31 of a pivoted operating lever 32 having a handle 33 by means of which shifting of the clutch shipper can be effected. The rod 26 carries three grooves 35, 36 and 37 adapted to coact with any suitable type of detent means (not shown) and respectively to hold the parts in position for driving the truck wheels, in the neutral position shown, and in position for driving the sleeve 13 and drive pulley 14. A multiple V belt is provided at 38 to transmit rotation to the fly-wheel and drive pulley 39 of the compressor 3.

The engine 2 is herein of the internal combustion type and provided with a carburetor 41, with a suitable conventional throttle valve 42 designed to be opened and closed manually to control the quantity of fuel mixture drawn into the intake manifold of the engine, with a governor valve mechanism 43 between the throttle and the engine intake manifold, and a connection 44 opening into the intake manifold 45 of the engine. The construction of the governor valve mechanism 43 is, in the main, not my invention. It includes an oscillatable valve mechanism 46 for throttling the intake passageway 47 leading to the intake manifold of the engine when the engine reaches a predetermined desired maximum speed. The valve mechanism 46 is mounted upon an oscillating shaft 48 which carries, at

one end thereof, an inertia member 50. A spring 51 is connected to a pin 52 carried by this inertia member 50, through a slotted eye member 53, and the opposite end of the spring is secured to a second threaded and eyed member 54. The member 54 is engaged by a pin 55 mounted in a slotted portion 56 of an adjusting block 57 mounted to reciprocate in guides 58 and 59, which may desirably be formed integral with a housing 60.

To enable the performance of the desired objects, I have provided modified and additional controlling means as follows: The block 57 is formed with a tapped bore 61, and in this I have threaded a special adjusting screw 62 formed at 15 the end of a rotatable adjusting rod or shaft 63 having a knurled handle 64. A flat 65 is provided upon the side of the rod 63 so that after adjustment has been made a holding screw 66 may be screwed in and prevent rotation of the rod 63 20 and a change in the spring tension. The tension of spring 51 normally urges the inertia member 50 towards a position such as is shown in Fig. 6, and an adjustable abutment screw 67 is provided to limit movement of the inertia member in a 25 direction opposite to that in which the spring acts, thereby to vary the distance of movement of the valve mechanism 46 toward its closed position. Surrounding the outer end of the rod 63 I have provided a threaded sleeve 68 welded to 30 a portion of the governor case. This sleeve is provided with diametrically opposite slots 69, and a pair of nuts 70 and 71 may be adjusted along the sleeve to vary the depth to which an element may move within the slots 69. A head 72, 35 herein shown with diametrically opposite V-shaped projections 73, is secured in any suitable manner, as by welding, to a sleeve 74 surrounding the rod 63 and extending within the bore of the stationary threaded sleeve 68. An arm 75 is 40 secured to the head 72 and may be turned about the axis of the sleeve 74 by means hereinafter described. The operating means for the arm 75 includes a Bowden wire 80 leading to the lower end of a pivoted lever arm 81 (Fig. 45) swingable about a pivot pin 82 carried by the truck frame. Stops 83 and 84 in the form of adjustable abutment screws are provided to limit the range of swing of the arm 81. A rod 85, pivotally connected at 86 to the lever 81, carries stop collars 87 and 88 between which a pair of springs 89 and 90 are arranged; and these springs engage the opposite sides of a rotatable pin 91 carried by the lever arm 81 and traversed by an opening 92 through which the rod 85 extends. 55 The springs 89 and 90 operate on the opposite sides of the pin 91.

Referring again to the governor valve mechanism 43, it will be noted that the position of the valve mechanism 46 is controllable automatically by the engine vacuum. Mounted on the casing of the mechanism 43 as shown most clearly in Fig. 11 is a cylinder 92 containing a reciprocating piston 93. Secured to this piston is a plunger 94 guided in a bore 95 formed in a sleeve integral 65 with the casing of the cylinder 92. This plunger engages the valve mechanism 46. A spring 96 surrounding the plunger acts on the piston to urge it to the right in Fig. 11. A passage 97 connects the cylinder at the right hand side of the piston to atmosphere, through an air filter 98. The plunger 94 has an axial passage 99 connecting the cylinder at the left hand side of the piston with the intake passage of the engine. When a vacuum is created within the engine intake 75

passage, the pressure at the left hand side of the piston 93 is reduced through the passage 98, and the atmospheric pressure acting on the right hand side of the piston effects movement of the latter against the reaction of the spring toward the left, thereby to vary the position of the governor valve 46 automatically in accordance with the pressure conditions within the engine intake passage 41. Patent No. 2,081,825, granted May 25, 1937, to W. E. Liebing et al., discloses in greater detail those constructional features which I have modified and supplemented to provide the present illustrative embodiment of the invention.

It will be evident that the automatic throttle 15 governor and the manual control for the throttle both act to control the valve mechanism 46 and are both mounted on the casing of the mechanism 43. In this instance the control rod 63 and the plunger 94 are arranged in parallel offset 20 relation at the opposite sides of the governor valve casing. It will be evident that various other arrangements may be resorted to and in certain constructions the control rod and plunger 25 might even operate separate governor valves instead of the single valve shown. Also the improved manual control may be associated with other types of governor valve mechanisms.

The mode of operation of my improved control means will be clearly apparent from the description given.

Now, it will be evident that moving the handle 33 of the lever 32 into the full-line position shown in Fig. 3 will result in a shifting of the clutch element 19 (Fig. 2) to effect engagement between the teeth 17 and 18; also, it will result in a swinging of the lever 81 to the position shown in full lines in Fig. 3, with a corresponding movement, through the Bowden wire 80, of the lever arm 75 to the position shown in Fig. 5. This position of the arm 75 brings the V-shaped projections 13 into such relation to the sleeve 68 that there is a bodily movement of the adjusting rod 63 and screw 62 to the right as viewed in Fig. 8, thus permitting the sliding block 56 also to move to the right, and the tension of the spring 51 to be reduced, with the result that the inertia member 50 is permitted to move to the position shown in Fig. 4 and the governor valve 46 is caused to move a certain distance in the closing direction. It will be appreciated that the spring 51 will continuously maintain the knurled handle 64 on the rod 63 against the surface of the lever arm 75, and that rotation of the lever arm 75 from the position shown in Figs. 4 and 5 to that shown in Figs. 6 and 7 will cause the V-shaped projections 13 to climb out of the notches 69 and rest upon the rearward end of the sleeve 68, thereby increasing the tension of the spring 51. On the other hand, shifting the lever arm 75 from the position shown in Fig. 7 to that shown in Fig. 5 will reduce the tension of the spring 51. When the handle 33 of the control lever 32 is moved to the dotted-line position shown in Fig. 3, the clutch element 19 will be moved to connect the shaft sections 5 and 6 and to interrupt compressor drive; and the higher engine speed desired for road operation than for compressor drive will be provided, since the corresponding movement of the lever 32 to the dotted-line position in Fig. 3 will, through the Bowden wire, cause the lever arm 75 to move in such a manner as to cause the V-shaped projections 13 to travel up the slopes of the slots 69, and thus to effect a movement of the rod 63 and screw 62 and sliding block 56 to the left, increasing the tension of the spring 51 and

opening the governor valve 46 leading to the engine intake to a greater degree.

From the foregoing description it will be apparent that I have provided an improved means for adjusting a governing valve; that I have provided improved means for actuating said adjusting means to cause an adjustment of the engine speed in accordance with the load which the engine is caused to drive. It will further be evident that I have provided an improved portable compressor outfit having improved means for changing the load upon the engine from transport to compressor drive, and concurrently and in the same operation changing the governor of the engine so that the latter will automatically provide a lower maximum speed during compressor drive than during transport. It will also be evident that the changing of the engine governor from road operating conditions to compressor operating conditions, automatically occurs whenever the operator shifts the control lever for the clutch which connects or disconnects the compressor drive, so that the proper engine control and the most effective engine speed are at all times obtained.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In combination, a portable base having a drive shaft rotatable to effect propulsion of said base, an engine supported by said portable base, a compressor supported by said portable base, a governor for said engine, means for selectively transmitting to the drive shaft of said portable base or to the compressor the power of said engine, and means for automatically changing the adjustment of said governor to regulate the maximum engine speed in accordance with the mechanism driven thereby.

2. In combination, a portable base having a drive shaft rotatable to effect propulsion of said base, a compressor supported by said portable base, an engine mounted on said portable base, means for selectively connecting said engine in driving relation with said compressor or said drive shaft, a governor for said engine, and means for simultaneously changing the driving connection of said engine and automatically altering the operation of said governor.

3. In combination, a portable base having propelling means, an engine mounted on said base and having governing means, means adapted to be driven by said engine and mounted on said base, means for selectively connecting said base propelling means and said driven means to said engine for driving thereby, and means for automatically changing the adjustment of said governing means to regulate the maximum engine speed in accordance with the particular means driven by said engine.

4. In combination, a portable base having propelling means, an engine mounted on said base and having governing means, means adapted to be driven by said engine and mounted on said base, means for selectively connecting said base propelling means and said driven means to said engine for driving thereby and including a manual control element for controlling the connec-

- 2,213,196
- tion of said driven means to said engine, and means operated by said control element for changing the adjustment of said governing means to regulate the maximum engine speed automatically in accordance with the particular means driven by said engine.
5. In combination, a portable base having propelling means, an engine mounted on said base and having governing means, means adapted to be driven by said engine and mounted on said base, means for selectively connecting said engine in driving relation with said base propelling means or said driven means, and means for simultaneously changing the connections of said means with said engine and automatically altering the operation of said governing means.
6. In combination, an internal combustion engine, a load shifter therefor, a governor valve for said engine, means for controlling the position of said valve in accordance with the engine intake vacuum, and means for regulating the responsiveness of said controlling means to vacuum variations including an element rotatable to vary such responsiveness, and means for rotating said element automatically when said load shifter is operated.
7. In combination, an engine, alternative loads therefor having different limit speeds, a governor for said engine having a control element varying in position with the engine speed and also having a resistance element regulating the responsiveness of said governor, and means for changing the resistance imposed by said element at given
- 10 15 20 25 30
- engine speeds automatically upon connection to said engine of one of said loads and disconnection of the other, and vice versa.
8. In combination, an engine and two devices to be driven thereby, a governor valve in said engine for limiting the maximum speed thereof, means for controlling the position of said valve in accordance with engine intake vacuum, means for selectively connecting said engine in driving relation to different ones of said devices, means operated by said connecting means for automatically altering the position of said governor valve as the driving connections are changed, and means for varying the responsiveness of said controlling means to vacuum variations in accordance with the change in position of said governor valve.
9. In combination, a prime mover, a plurality of devices to be driven by said prime mover and having different limit speeds, means for selectively connecting said prime mover in driving relation with said devices, means for supplying a motive medium to said prime mover, a governor for said supply means having a valve arranged to be actuated toward closed position by the flow of motive medium to said prime mover, yieldable means for resisting movement of said valve toward closed position, and means operated by a part of said connecting means for varying the resistance of said yieldable means in accordance with the device driven by said prime mover.
